CLAIM

Dec. 14, 1999 (JP) 11-34427

The ornamental design for a stator of AC generator for vehicles, as shown and described.

(51) LOC (7) Cl. **13-01**

DESCRIPTION

(52) U.S. Cl. **D13/122**

FIG. 1 is a front, and top side perspective view of a stator of AC generator for vehicles showing our new design;

(58) Field of Search D13/118, 122;

FIG. 2 is a front elevational view thereof;

310/52, 179, 180, 201, 254-260

FIG. 3 is a top plan view thereof;

310/180

FIG. 4 is a rear elevational view thereof;

4,741,098 * 5/1988 Barrera 29/736

FIG. 5 is a bottom plan view thereof;

5,640,062 * 6/1997 Yockey ..... 310/68 D

FIG. 6 is a right side elevational view thereof;

5,998,903 * 12/1999 Umeda et al. 310/179

FIG. 7 is a left side elevational view thereof; and,

6,049,154 * 4/2000 Asao et al. 310/201

FIG. 8 is a front, and top side reference perspective view showing a part of the armature coils of the stator.

6,051,906 * 4/2000 Umeda et al. 310/179

The broken line showing in FIG. 8 is included for the purpose of indicating a continuous array of the single armature coil part as shown in FIG. 1.
